UNITED STATES PATENT OFFICE

FREDRICH BOHNENBERGER, OF NEW YORK, N. Y., ASSIGNOR TO MULFORI
HALE & COTTLE, OF SAME PLACE.

DESIGN FOR FINGER-RINGS.

Specification forming part of Design No. **7,453**, dated May 26, 1874; application filed March 14, 1874.
[Term of Patent 3½ years.]

To all whom it may concern:

Be it known that I, FREDRICH BOHNENBERGER, of the city, county, and State of New York, have invented a Design for Finger-Rings, of which the following is a specification:

Figure 1 is a side view of a ring illustrating my design. Fig. 2 is an edge view of the same. Fig. 3 is a section of the same, taken through the line *x x*, Fig. 2.

My design has reference exclusively to the annular shank or portion of the ring, irrespective of the enlarged socket for the stone.

As shown in the drawing, the shank is flat on each side A, and the space between is oc-

cupied, exteriorly, by deep round grooves and ribs C. I do not, however, restrict myself in the number of either grooves or ribs. For example, there may be one groove and two ribs, two grooves and one rib, or an equal number of each. The ribs may, also, be plain or milled, as preferred.

What I claim is—

The design for a finger-ring formed of flat side portions A, ribs C, and grooves B, as shown and described.

FREDRICH BOHNENBERGER.
